UNITED STATES PATENT OFFICE

ANDY MAURER, OF ROUND MOUNTAIN, CALIFORNIA

REVERSIBLE PLOW

Application filed June 18, 1930. Serial No. 462,082.

The present invention relates to new and useful improvements in reversible plows and more particularly to that class adapted to be used as a breaking plow and the object is to provide means for attaching a plow share at each edge of the moldboard.

A further object is to provide means for pivotally mounting the mold board in position on the standard of the plow and a further object is to provide means for holding the mold board in adjusted position.

A still further very important object of the invention resides in the provision of a reversible plow of this nature which is exceedingly simple in its construction, inexpensive to manufacture, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a plow embodying the features of my invention,

Figure 2 is a similar view taken opposite to that shown in Figure 1,

Figure 3 is a top plan view thereof,

Figure 4 is a fragmentary perspective view showing the standard,

Figure 5 is a perspective view of the holding means,

Figure 6 is a rear elevation of the plow,

Figure 7 is a sectional view taken substantially on the line 7—7 of Figure 1, and

Figure 8 is a sectional view taken substantially on the line 8—8 of Figure 1.

Referring to the drawings in detail it will be seen that the numeral 1 indicates the beam of the plow, which may be constructed in any preferred manner and 2 indicates the standard depending therefrom and to the lower end of said standard is pivotally secured my improved form of mold board 3.

The upper and lower edges of the mold board 3 have secured thereto the usual form 50 of plow shares 4 while the forward edge of

the moldboard is concaved to form a cutting edge, said cutting edge being so formed as to cooperate with the inclined face of the plow share and causing said moldboard to properly scour.

The lower edge of the standard 2 merges into a horizontal sleeve 5 through which extends a bolt 6. A supporting strap 7 is riveted or otherwise secured to the forward edge of the moldboard and at the center is formed with a bearing 8 circumjacent the forward end of the bolt 6. Straps 9 project rearwardly and horizontally from the plow shares 4 and are offset as at 10 to receive the horizontally disposed end portions 11 of a vertical bracket or brace member 14 which is riveted to the mold board 3, the end portions 11 being bolted to the offset portions 10 of the straps 9 as at 12.

A supporting strap 15 is disposed between the straps 9 and has an arcuate intermediate portion 16 about the rear portion of the bolt 6. A reinforcing strap 17 is bolted as at 18 to the supporting strap 15 and has an arcuate intermediate portion 19 circumjacent the bolt 6. Thus it will be seen that the moldboard 3 is rockable on the bolt 6 to be placed either in the full line position in Figure 6 or in the dotted line position thereof.

A U-shaped holder 20 is rockably mounted by a bolt 21 through the juncture of the plow beam 1 with the standard 2, said bolt extending through the sides of the U-shaped holder so that the ends thereof may straddle the strap 9 which is uppermost.

A handle 23 projects from the cross central portion of the holder 20 for easy manipulation thereof.

This form of plow is particularly adapted in case of rolling or hilly land, but it will be understood that the same can be used for turning all kinds of soil and it will likewise be seen that the moldboard can be practically instantly changed to produce a right or left hand plow.

The present embodiment of the invention has been disclosed in considerable detail merely for the purposes of exemplification since in actual practice it attains the features of advantage enumerated as desirable in the

statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In a plow construction, the combination of a beam having a standard terminating in a sleeve, a bolt extending through the sleeve and projecting beyond the ends thereof, a double mold board, a supporting strap on the land side of the front edge portion of the mold board and having a bearing at the center thereof journalled about the forward end portion of the bolt, a share at each edge of the mold board and merging in rearwardly extending horizontal straps, a vertical supporting strap between the rear end portions of the horizontal straps and having an arcuate portion about the rear end portion of the bolt, a reinforcing strap fixed to the vertical supporting strap having an arcuate portion about the rear end portion of the bolt.
2. In a plow construction, the combination of a beam having a standard terminating in a sleeve, a bolt extending through the sleeve and projecting beyond the ends thereof, a double mold board, a supporting strap on the land side of the front edge portion of the mold board and having a bearing at the center thereof journalled about the forward end portion of the bolt, a share at each edge of the mold board and merging in rearwardly extending horizontal straps, a vertical supporting strap between the rear end portions of the horizontal straps and having an arcuate portion about the rear end portion of the bolt, a reinforcing strap fixed to the vertical supporting strap having an arcuate portion about the rear end portion of the bolt, a substantially U-shaped bracket having an intermediate portion fixed to the rear portion of the mold board and having its ends fixed to the horizontal straps.
3. In a plow construction, the combination of a beam having a standard terminating in a sleeve, a bolt extending through the sleeve and projecting beyond the ends thereof, a double mold board, a supporting strap on the land side of the front edge portion of the mold board and having a bearing at the center thereof journalled about the forward end portion of the bolt, a share at each edge of the mold board and merging in rearwardly extending horizontal straps, a vertical supporting strap between the rear end portions of the horizontal straps and having an arcuate portion about the rear end portion of the bolt, a reinforcing strap fixed to the vertical supporting strap having an arcuate portion about the rear end portion of the bolt, a substantially U-shaped bracket having an intermediate portion fixed to the rear portion of the mold board and having its ends fixed to the horizontal straps.

substantially U-shaped bracket having an intermediate portion fixed to the rear portion of the mold board and having its ends fixed to the horizontal straps, a substantially U-shaped member rockably mounted on the juncture of the plow beam with the standard and adapted to be swung to straddle one of the horizontal straps for holding the mold board in adjusted position.

In testimony whereof I affix my signature.

ANDY MAURER.
